UNITED STATES PATENT OFFICE.

ANTHONY DIXON BROGAN AND ANDREW MURRAY MALLOCH, OF GLASGOW,
SCOTLAND.

DESIGN FOR PLATE-GLASS.

SPECIFICATION forming part of Design No. 36,444, dated July 14, 1903.

Application filed May 28, 1903. Serial No. 159,215. Term of patent 14 years.

To all whom it may concern:

Be it known that we, ANTHONY DIXON BROGAN and ANDREW MURRAY MALLOCH, citizens of the United Kingdom of Great Britain and Ireland, residing at Firhill, in the city of Glasgow, county of Lanark, Scotland, have invented a new, original, and ornamental Design for Plate-Glass, of which the following is a specification, reference being had to the accompanying drawing, forming part thereof.

The figure is a plan view of a pane of plate-glass bearing our new design, the said design being fully and clearly represented and shown

in the said figure, so as to need no verbal description.

Having thus described our invention, what we claim as new, and desire to secure by Letters Patent, is—

The ornamental design for plate-glass, as herein shown.

In witness whereof we have hereunto set our hands in presence of two witnesses.

ANTHONY DIXON BROGAN.
ANDREW MURRAY MALLOCH.
